(57) **CLAIM**

The ornamental design for a detergent tablet, as shown and described.

DESCRIPTION

FIG. 1 is a perspective view of a detergent tablet showing the new design;

FIG. 2 is an end view thereof both ends appearing the same;

FIG. 3 is a side view thereof both sides appearing the same; and,

FIG. 4 is a top plan view.

The stippling in the drawings is representative of color contrast, not pattern. The surface(s) or portion(s) of the article not shown in the drawing or described in the specification form(s) no part of the claimed design.
